UNITED STATES PATENT OFFICE.

THOMAS P. TAYLOR, OF BRIDGEPORT, CONNECTICUT.

FISH-POLE HOLDER.

SPECIFICATION forming part of Letters Patent No. 314,751, dated March 31, 1885.

Application filed July 5, 1884. (No model.)

To all whom it may concern:

Be it known that I, THOMAS P. TAYLOR, a citizen of the United States, residing at Bridgeport, in the county of Fairfield and State of Connecticut, have invented certain new and useful Improvements in Fish-Pole Holders; and I do hereby declare the following to be a full, clear, and exact description of the invention, such as will enable others skilled in the art to which it appertains to make and use the same.

My invention has for its object to produce a device for holding fish-poles. When fishing from a boat and using several poles, it is sometimes quite difficult to keep them in the desired position, especially if the water is rough or the wind blows. The way common to many fishermen has been to lay an oar across from one of the seats to the opposite side of the boat from that being fished from, and simply rest the butts of the poles under the oar; but if it is desired to fish from the other side of the boat, everything has to be moved, making it very unpleasant if there is more than one person in the boat, and if a sudden gust of wind comes or the boat gives a lurch the poles are very apt to come together, tangling the lines, &c.

My invention is intended to produce a device which will be exceedingly simple in construction and inexpensive to manufacture, and which can be quickly and firmly attached by screws or bolts, or in any desired manner, to the edge of a boat, and which will hold the poles in such a manner that the wind cannot blow them loose, and yet they can be instantly taken up by the hand when desired.

In the accompanying drawings, forming part of this specification, Figure 1 is a side elevation with a portion of the side of a boat shown in section. Fig. 2 is a rear elevation of the device detached; Fig. 3, a plan view, and Fig. 4 a perspective of a modified form of the device.

A is a plate, preferably of metal; and B, a shank or bracket made integral therewith, by means of which the device is attached to the side of the boat by screws or bolts, or in any suitable manner. The outer face of the shank or bracket B is formed at an obtuse angle to the plate or body of the holder, so that the

said face may fit against the inside of the boat, and the holder be so placed as to properly elevate the outer ends of the pole or poles sustained thereby.

It will of course be understood that the shape and size of plate A is not of the essence of my invention, as numerous variations may be made without departing in the slightest from the spirit of my invention. I preferably, however, construct the plate substantially in the form illustrated in Figs. 1, 2, and 3.

C in Fig. 1 represents the side of the boat, the back portion of plate A being shown as resting upon the edge thereof. At the back of the plate, on its upper surface, I provide hollows or depressions D, in which the fish-poles rest. These hollows are preferably cast in the plate; but the same result may be accomplished by pins placed in the top of the plate at suitable distances apart. At the opposite side of the plate—i. e., the front, as it appears when in position—I provide hollows or sockets E upon the under side of the plate, which hold the butts of the poles in place. I have shown the plate as arranged to hold two poles only, which (owing to the fact that hollows E, in which the butts of the poles rest, are closer together than hollows D upon the top of the plate) project from the side of the boat at an angle to each other. This, however, is merely incidental, as the plates may be arranged to hold a larger number of poles, and the angles at which the poles project may be arranged to correspond with the number used.

In the modification illustrated in Fig. 4, which is intended to hold but one pole, a wire, F, having a curve in which the pole rests, is substituted for plate A, the part corresponding with the shank or bracket in the other form being extended above the side of the boat, and provided with a hollow or socket, G, in which the butt of the pole rests. H in Fig. 4 represents a pole as it appears in place. This figure illustrates the operation of the device fully. It will be seen that in either form the butts of the poles are firmly held in sockets, which, however, permit the poles to be readily lifted, the hollows or depressions upon the opposite side of the plate serving as rests, and at the same time preventing the poles from

slipping around should the wind blow or the boat be unsteady from any cause.

The whole device may be made of wood, cast in one piece from metal, or made by bending heavy wire into the required shape.

Having thus described my invention, I claim—

1. A fish-pole holder having an upwardly-open hollowed rest adapted to support the pole and to prevent its lateral displacement, an overhanging hollowed support for the butt of the pole, and an attaching shank or bracket, the outer face of which is at an obtuse angle to the body of the holder, substantially as set forth.

2. A fish-pole holder consisting of an open plate having at one side a rest with upwardly-open hollows or depressions, and at its other side an overhanging support for the butts of the poles, having hollows or depressions on its under side, said plate being provided with an attaching shank or bracket, the outer face of which is at an obtuse angle to the body of the holder, substantially as set forth.

In testimony whereof I affix my signature in presence of two witnesses.

THOMAS P. TAYLOR.
